US00D681076S

(12) **United States Design Patent**
Sata et al.(10) **Patent No.:** **US D681,076 S**
(45) **Date of Patent:** **** Apr. 30, 2013**(54) **REFRIGERATING MACHINE**(75) Inventors: **Hiroshi Sata**, Chiyoda-ku (JP); **Kenichi Hata**, Chiyoda-ku (JP)(73) Assignee: **Mitsubishi Electric Corporation**,
Tokyo (JP)(**) Term: **14 Years**(21) Appl. No.: **29/419,987**(22) Filed: **May 3, 2012**(51) **LOC (9) Cl.** **15-07**(52) **U.S. Cl.**USPC **D15/91**(58) **Field of Classification Search** **D15/79-89**,
D15/91; 62/3.1, 3.63, 3.64, 389, 391, 440,
62/448, 261, 229, 407, 519-520, 523, 472,
62/476; 312/401-408, 116, 138.1

See application file for complete search history.

Primary Examiner — Mitchell Siegel(74) *Attorney, Agent, or Firm* — Sughrue Mion, PLLC(57) **CLAIM**The ornamental design for a refrigerating machine, as shown
and described.**DESCRIPTION**FIG. 1 is a front, top and right side perspective view of a
refrigerating machine, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
